UNITED STATES PATENT OFFICE.

JAMES EDWARD FLITCROFT, OF OCEAN GROVE, NEW JERSEY, ASSIGNOR TO OTTO BERNZ, OF NEWARK, NEW JERSEY.

PLUMBER'S TEST APPARATUS.

1,116,876.

Specification of Letters Patent. Patented Nov. 10, 1914.

Application filed August 20, 1914. Serial No. 857,676.

To all whom it may concern:

Be it known that I, JAMES EDWARD FLITCROFT, a citizen of the United States, residing at Ocean Grove, in the county of Monmouth and State of New Jersey, have invented certain Improvements in Plumbers' Smoke-Test Apparatus, of which the following is a specification.

This invention relates more particularly to improvements in that class of testing apparatus in which smoke is employed as a medium to be discharged into a pipe system, such as the drain or water system of a house, the smoke finding its escape through any defects in the system and thus giving warning of the imperfection.

The objects of the invention are to provide such an apparatus which is free from valves; to render the fire or smoke pot readily accessible; to admit an increase in volume of smoke; to provide means for observing a decrease in volume of the smoke as a result of a leak; to introduce air to the fire or smoke pot under pressure; to seal the air passage to back-flow and escape of smoke therethrough; to provide means for determining whether the smoke is being formed and passed to the pipe system properly; to secure simplicity of construction and operation, and to obtain other advantages and results as may be brought out in the following description.

Referring to the accompanying drawings, in which like numerals of reference indicate the same parts throughout the several views. Figure 1 is a plan of my improved testing apparatus; Fig. 2 is a vertical longitudinal section on line A—A thereof; Fig. 3 is a sectional view on line B—B of Fig. 2; Fig. 4 is a transverse section on line C—C of Fig. 3, looking in the direction indicated by the arrows, and Fig. 5 is a similar section on line D—D of Fig. 3, with the cover in place and looking in the opposite direction, as shown by the arrows.

In the specific embodiment of the invention illustrated in said drawings, the reference numeral 1 indicates a tank or container adapted to contain a fluid, such as water, in which the apparatus is placed to keep it cool and seal it. In this instance the tank is shown rendered impervious by an interior lining 2, which is preferably of sheet metal. Within said tank and preferably adjacent one end thereof, is an up-

wardly projecting fire or smoke pot 3, shown as a generally cylindrical tube 4 fixed within the tank and providing an interior chamber; a cover 5 with a deep flange or skirt 6 is adapted to fit down loosely over the top of said tubular body 4 and close the open upper end thereof. The side wall of the pot body 4 is bent inward longitudinally at one side, forming a deep vertical groove or channel 7 from top to bottom, and mounted longitudinally within this channel 7 is a smoke outlet pipe 8 substantially flush at its top end with the top of the pot body 4. At the bottom of the body 4 this outlet pipe 8 is provided with a suitable fitting, such as an elbow 9 which turns laterally away from said body 4 and receives a nipple 10 which extends through the end wall of the tank 1. Upon the outside of the tank the nipple screws into a coupling 11 adapted to be connected to the pipe system to be tested and also having a test opening 12 normally closed by a plug 13. A ring like bracket 14 is secured to the outside of the tank and supports the connecting end of the coupling 11.

It is to be understood that the outlet pipe 8 which extends upwardly within the channel 7 is inclosed within the cover 6, and that communication from the chamber 5 to said pipe may be had over the top edge of the wall of said chamber beneath the cover. Such communication is insured by shaping the top of the cover as a dome, so that the rounded corners engage the pot body 4 before either the pipe 8 or chamber are sealed to each other. From the center of the dome-like top of the cover a removable guide rod 15 extends upward and passes slidably through the eye 16 of a bracket 17 supported by the tank. Preferably this bracket is of bent wire and its foot seats removably in the socket 18 of a bracket base 19 secured to the end of the tank by screws, a set screw 20 working through the side of the socket to clamp the bracket in its socket.

An inlet 21 leads into the lower part of the smoke pot 3, near its base, and preferably at the opposite side thereof from the outlet pipe 8, and it is to be understood that suitable fittings are provided to pass said inlet pipe 21 from the exterior to the interior with an impervious joint. Upon the outside of the smoke pot the inlet pipe is turned upward as at 22 and extends above

105

110

the top of the tank 1 adjacent its end opposite that through which the outlet 8 extends. Over this upturned part 21 of the inlet pipe is inverted a box or hood 23 soldered or otherwise held to the end and side walls of the tank or container for support so as to hold the lower open end of the hood a little above the bottom of the tank, the bottom edge of the hood being notched or recessed 5 as at 24 to accommodate the pipe 21. Into the top of the hood leads an air injector 25 shown as consisting of a nozzle 26 connected by a suitable connection 27 to an air pump 28. The nozzle leads into an upwardly 10 flared end 29 of an air supply pipe 30 which extends downward through the closed top of the tank 1 to a short distance below it, said nozzle being supported on the flared top or end 29 by a spider frame 31 providing 15 crossed arms or radial bars between which air may be drawn inward by the energy of the air passing inward from the nozzle.

In use, the outlet pipe 8 is coupled to the system of piping to be tested and the tank 25 1 filled with water substantially to its top or as near thereto as can be conveniently done without overflow. This water seals the lower end of the air supply pipe 30 to backflow or sewer gas, but obviously the pump 30 will force air through said supply pipe which being under pressure will displace the water and bubble to the surface, trapped in the upper end of the box or hood 23. The only outlet from this upper end of the 35 hood being through the inlet pipe 22, 21 to the smoke pot, the air passes thereto. Waste or other smoke-creating material may be ignited within the smoke pot, as is usual a raised or false bottom 32 being provided 40 therein to prevent undue heating of the bottom of the box. The air supply affords oxygen for the combustion of said material, and also a draft and pressure to carry the smoke into the outlet 8 and piping system. 45 Obviously the water in the tank seals the passage between the smoke pot cover 6 and pot body 4 against the escape of smoke.

In order to lessen the agitation of the 50 water, in the tank 1, as in lifting it about, preferably a baffle plate 33 is removably supported between the smoke pot 3 and the hook 23, although this plate is not impervious to passage of water, and its bottom edge is notched or recessed as at 34 to accommodate the pipe 21.

If there are no leaks in the piping system being tested, the smoke pot cover 6 will rise under the pressure exerted by the air pump, or if the leaks are small the dome will rise. 60 Then if pumping is discontinued and the dome does not fall, it indicates that the system is tight, whereas if the dome sinks back to normal position the operator knows there is a defect in the system and can then locate 65 it by the smoke escaping through the

leak. During any stage of the test the operator may ascertain whether the waste in the smoke pot is burning properly and smoke passing into the pipe system, or whether the waste is flaming and burning 70 without smoke, by removing the plug 13 from the test opening 12. Obviously if smoke issues from this opening at such time it can be assumed that smoke is passing to the pipe system being tested. When the test 75 has been completed the air pump 28 may be disconnected, the water poured out, the bracket 17 removed from the tank, the guide rod 15 removed and a cover 35 fastened over the top of the tank as by hasps 36, 36, a suitable handle 37 affording convenient means for transporting the device.

Having thus described the invention, what I claim is.

1. In a smoke test apparatus, the combination of a tank adapted to contain water, a smoke pot in said tank having an upwardly movable cover adapted to extend beneath the water, an outlet leading from the upper part of said smoke pot, an inlet leading from above the level of the water to the smoke pot, a hood inverted over the top of said inlet adapted to extend beneath the water, and means for introducing air into said hood beneath the level of water therein. 95

2. In a smoke test apparatus, the combination of a tank adapted to contain water, a smoke pot in said tank having an upwardly movable cover extending beneath the water, an outlet leading from an upper part of said pot downward and out through the wall of the tank, an inlet leading from above the top of the tank downward to a lower part of the smoke pot, a hood over the top of said inlet extending beneath the water, a nozzle extending through said hood and terminating beneath the water, and means for forcing air in through said nozzle. 100

3. In a smoke test apparatus, the combination of a tank adapted to contain water, a smoke pot body projecting upward from the bottom of said tank and open at its top, an outlet pipe at the side of said pot body leading at its lower end through the wall of the tank, a cover with a deep skirt or flange 110 loosely inclosing the tops of said pot body and outlet pipe, an inlet leading from the top of the tank downward to the smoke pot, a hood over said inlet and extending beneath the water, and means for introducing air 115 into said hood below the level of water therein. 120

4. In a smoke test apparatus, the combination of a tank adapted to contain water, a smoke pot body projecting upward from the bottom of said tank above the level of the water, said body being open at its top and having a longitudinal groove or recess in its outer wall, an outlet pipe in said groove or recess having its upper end at the top of the 125 130

pot body and its lower end leading out of the tank, a cover loosely inclosing the tops of said pot body and outlet pipe and having a deep skirt or flange extending below the 5 level of water, an inlet leading from above the level of water to the smoke pot, a hood over the top of said inlet and extending beneath the water, and means for introducing air into said hood beneath the level of water 10 therein.

5. In a smoke test apparatus, the combination of a tank adapted to contain water, a smoke pot body projecting upward from the bottom of said tank above the level of the 15 water and being open at its top, an outlet leading from the upper part of said smoke pot, a cover loosely inclosing the tops of said pot body and outlet and having a deep skirt or flange extending below the level of water, 20 a stem removably secured to said cover, a detachable guide bracket for said stem on the tank, an inlet leading from above the level of water to the smoke pot, a hood over the top of said inlet adapted to extend beneath the water, a nozzle for introducing air into 25 said hood beneath the level of water therein, and a lid or top for the tank adapted to be separably connected thereto and inclose all said parts when the stem and bracket are detached. 30

6. In a smoke test apparatus, the combination of a tank adapted to contain water, a smoke pot fixed in one end of said tank and

having an upwardly movable cover adapted to extend beneath the water, an outlet leading from the upper part of said smoke pot, an inlet leading from above the level of water to the smoke pot, said inlet located at the opposite end of the tank from the smoke pot, a hood over the top of said inlet adapted 40 to extend beneath the water and secured to the tank, means for introducing air into said hood beneath the level of water therein, a baffle plate between said hood and smoke pot, and a lid or top for the same adapted to 45 inclose said parts.

7. In a smoke test apparatus, the combination of a tank adapted to contain water, a smoke pot body in said tank extending upward above the level of water and having an 50 open top, a loosely telescopic cover for said pot body having a deep skirt or flange extending beneath the level of the water, an inlet leading from above the level of the water downward to the lower part of the smoke 55 pot, a hood over said inlet extending beneath the level of the water, means for introducing air into said hood beneath the level of water therein, and an outlet pipe extending beneath said smoke pot cover above the 60 level of water therein.
